UNITED STATES PATENT OFFICE.

DAVID F. VAUGHAN, OF RIVERTON, NEW JERSEY.

ANTICREEPER FOR RAILROAD-RAILS.

1,276,457.

Specification of Letters Patent. Patented Aug. 20, 1918.

Application filed January 22, 1918. Serial No. 213,122.

To all whom it may concern:

Be it known that I, DAVID F. VAUGHAN, a citizen of the United States, residing at Riverton, in the county of Burlington and State of New Jersey, have invented certain new and useful Improvements in Anticreepers for Railroad-Rails, of which the following is a specification.

My invention relates to improvements in that type of anticreepers for railroad rails, which are adapted to grip a rail base and engage a stationary part of the road bed and thereby prevent the creeping or longitudinal displacement of the rail.

The object of my invention is to provide an anticreeper possessing novelty and utility wherein a single element may be caused to grip a rail base by the resiliency or spring action thereof, engaging the bottom of the rail base and the top of the respective sides of the same with a twisting force exerted by said element, as it tends to resume its normal condition from which it is sprung when applied to the rail base and thereby produce a grip upon the rail which shall be strong, durable and efficient under all conditions when the anticreeper is in service.

With the above and related objects in view, my invented anticreeper consists of the novel construction, combinations and arrangements of the elements thereof, as will be hereinafter fully described and particularly claimed.

In the accompanying drawings, illustrating my invention.

Figure 1 is a plan view of my improved anticreeper applied to a railroad rail adjacent to a cross-tie.

Fig. 2 is a side elevation thereof.

Fig. 3 is a cross section through the rail, on line 3-3 of Fig. 2, showing the anticreeper in the distance.

Fig. 4 is a view, showing the device in position to be applied to the rail.

Fig. 5 is a view of a modified form of the anticreeper applied to the rail.

Fig. 6 is a plan view of the parts shown in Fig. 5.

Fig. 7 is a view of the separate spring element employed with the anticreeper shown in Figs. 5 and 6.

Referring to the drawings, 2 designates a portion of a cross-tie and 4 a railroad rail supported thereon. The cross-tie 2 forms a stationary part of the road bed, and the

rail 4 is of usual construction including the usual base 5.

My improved anticreeper is applied to the rail 4 and is of the following construction: Extending transversely beneath the rail base 5 is a member or bar 6 which constitutes the body portion of the anticreeper. The bar 6 is arched or cambered, as illustrated, and the top of the arch or camber provides a bearing face 7 which is adapted to bear against the bottom of the rail base 5 inwardly of the side edges thereof and from which the end portions of the bar extend downwardly in spaced relation to the base 5.

One end of the bar 6 is provided with a jaw 8 which extends upwardly and inwardly therefrom and is provided with a lower bearing face 9 adapted to engage the top of one side of the rail base 5; and the other end of the bar 6 is provided with a jaw 10 which extends upwardly and inwardly therefrom and is provided with a lower bearing face 11 adapted to engage the top of the other side of the rail base 5.

When the anticreeper is in normal condition and before it is applied to the rail base 5, the parts of the device are related to each other as shown in Fig. 4; that is to say the bearing face 7 is closer to the bearing faces 9 and 11 than when the device is applied to a rail, or the bearing face 7 is above the plane of the bottom of the rail base 5 with relation to the bearing faces 9 and 11, as shown by dot-and-dash lines in Figs. 3 and 5, so that when the anticreeper is applied to the rail, as will be presently explained, the jaws 8 and 10 and the end portions of the bar 6 will be sprung apart to the condition shown by full lines in Figs. 3 and 5. In addition to the normal relation of the parts of the anticreeper, as just described, the jaws 8 and 10 are deflected laterally on the respective sides of the bar 6, as clearly shown in Fig. 1, for the purpose of exerting a twisting action on the entire device when it is applied to the rail.

The jaw 8 is made longer than the jaw 10, and the spaces between the jaws 8 and 10 and between them and the bar 6 are large enough to permit the application of the device to the rail laterally thereof by first hooking the jaw 8 over one side of the rail base 5, then raising the bar 6 to bring its bearing face 7 up against the bottom of the rail base 5 and bringing the bearing face 110

11 of the jaw 10 into line with the upper face of the adjacent side of the rail base 5, while the jaw 8 rests upon the top of the opposite side of the rail base, as shown in Fig. 4, and then striking the outer end of the jaw 10 and driving the entire device laterally of the rail in the direction of the arrow in Fig. 4, until the device occupies the position shown by full lines in Fig. 3. The device is formed of suitable spring metal, and, during the driving thereof into final position upon the rail base 5, the jaws 8 and 10 and the end portions of the bar 6 are sprung apart and the entire device is twisted within its elastic limit, due to the relative arrangement of the jaws 8 and 10 and the normal relation thereof to the bearing face 7, and, thereafter, as the entire device tends to untwist itself or return to its normal condition, it will grip the rail base 5 with great strength and firmness.

The device is applied to the rail base 5 adjacent to the cross-tie 2, as usual, and when the rail 4 tends to creep or to be longitudinally displaced, under the well known conditions, the device will engage the cross-tie 2 and prevent such displacement or creeping.

In Figs. 5 and 6 I have shown the bar 6 provided with a spring 12 which is seated in a socket 13 formed in the top of the bar 6. The spring 12 is preferably in the form of the usual well known nut lock washer, as shown in Fig. 7; and normally, when the spring 12 rests within the socket 13, the spring extends above the top of the bar 6, so that when the anticreeper is applied to the rail, as previously described, the spring 12 will be compressed and thereby exert additional pressure against the rail base 6 and thus increase the grip of the device upon the rail.

I claim:

1. An anticreeping device to be applied to the base of a railroad rail by springing the device from its normal condition, said device comprising a bar adapted to extend transversely beneath a rail base and having an upper bearing face adapted to engage the bottom of a rail base, and two jaws extending upwardly and inwardly from the respective ends of the bar and having lower bearing faces adapted to engage the top of the rail base, said upper bearing face being adapted to be strained to a position farther from the plane of the said lower bearing faces when the device is applied to a rail, and said jaws being disposed to exert a twisting action upon the device when it is applied to a rail.

2. An anticreeping device to be applied to the base of a railroad rail by springing the device from its normal condition, said device comprising a bar adapted to extend transversely beneath a rail base and having

an upper bearing face adapted to engage the bottom of a rail base, and two jaws extending upwardly and inwardly from the respective ends of the bar and having lower bearing faces adapted to engage the top of the rail base, said upper bearing face being adapted to be strained to a position farther from the plane of the said lower bearing faces when the device is applied to a rail, and said jaws respectively being deflected laterally on the respective sides of the bar to exert a twisting action upon the device when it is applied to a rail.

3. An anticreeping device to be applied to the base of a railroad rail by springing the device from its normal condition, said device comprising a cambered bar adapted to extend transversely beneath a rail base and to engage the bottom thereof, and two jaws extending upwardly and inwardly from the respective ends of the bar and adapted to engage the top of a rail base, said jaws being disposed to exert a twisting action upon the device when it is applied to a rail.

4. An anticreeping device to be applied to the base of a railroad rail by springing the device from its normal condition, said device comprising a bar adapted to extend transversely beneath a rail base and to engage the bottom thereof, and two jaws of unequal length extending upwardly and inwardly from the respective ends of the bar and adapted to engage the top of the rail base, said jaws being disposed to exert a twisting action upon the device when it is applied to a rail, and the spaces between said jaws and between them and the bar being large enough to permit the application of the device to a rail by moving the device laterally of the rail and hooking said jaws one in advance of the other over the respective sides of the rail base.

5. An anticreeping device to be applied to the base of a railroad rail by springing the device from its normal condition, said device comprising a bar adapted to extend transversely beneath a rail base and to engage the bottom thereof, two jaws extending upwardly and inwardly from the respective ends of the bar and adapted to engage the top of a rail base, said jaws being disposed to exert a twisting action upon the device when it is applied to a rail, and a spring carried by the bar and adapted to exert pressure against the same and a rail base when the device is applied to the latter.

6. An anticreeping device to be applied to the base of a railroad rail by springing the device from its normal condition, said device comprising a bar having a socket formed therein and being adapted to extend transversely beneath a rail base and to engage the bottom thereof, said device comprising a bar adapted to extend trans-

versely beneath a rail base and to engage the bottom thereof, two jaws extending upwardly and inwardly from the respective ends of the bar and adapted to engage the top of a rail base, said jaws being disposed to exert a twisting action upon the device when it is applied to a rail, and a spring

within said socket and adapted to exert pressure against the bar and a rail base when the device is applied to the latter. 10

In testimony whereof I affix my signature hereto:

DAVID F. VAUGHAN.
